UNITED STATES PATENT OFFICE

GRIFFITH OWEN DAVIES, OF HARROW, ENGLAND.

ELECTRIC-ACCUMULATOR PLATE.

1,098,231.

Specification of Letters Patent. Patented May 26, 1914.

Application filed February 2, 1914. Serial No. 816,072.

To all whom it may concern:

Be it known that I, GRIFFITH OWEN DAVIES, residing at 42 Marlborough Hill, Harrow, Middlesex, England, have invented 5 certain new and useful Improvements in Electric-Accumulator Plates, of which the following is a specification.

This invention relates to plates for electric accumulators or storage batteries of the 10 Plante type and particularly to those in which thin corrugated plates of lead reinforced at their edges are employed. Hitherto, owing to the flexibility of the thin corrugated metal, it has been customary to 15 make up the plate from a number of separate panels or small sections and to reinforce the edges by strips of U shape in cross section and consequently burning has been resorted to in order to connect the parts 20 together.

The object of the present invention is to enable a plate of thin corrugated metal to be produced of adequate size and rigidity without necessitating burning as it is found 25 that burnt parts rapidly deteriorate when the plate is in use.

With this object in view the invention resides in the use of reinforcing slats of light material such as wood, adapted to engage 30 with or fit the side edges of the plate and spaced at top and bottom by transverse stiffening distance pieces of wood, celluloid, vulcanite, xylonite, fiber or other suitable material. The side slats and transverse stiffening pieces, are preferably covered with a 35 suitable covering or paint to resist the attack of the acid in the cell.

The invention and the details thereof will be more readily understood from the following 40 description of two convenient forms illustrated by way of example in the accompanying drawings in which:—

Figure 1 is a side elevation of my improved plate. Fig. 2 is a section on the line 2—2 of Fig. 1. Fig. 3 is a section on the line 3—3 of Fig. 1. Fig. 4 is an enlarged cross section of a cast lead plate. Fig. 5 is a similar view of the same after it has been pressed. Figs. 6 and 7 are details. Fig. 8 is a view of 50 a second form of plate on a reduced scale.

In carrying the invention into effect according to the form shown in Figs. 1 to 3 the plate *a*, is formed without panels of thin corrugated lead, the plaits or corrugations of 55 which are arranged very closely together,

and the said plaits or corrugations extend vertically. The thickness of the corrugations which are employed is preferably about a quarter of an inch to three eighths, that is to say the dimension *b* in Fig. 2 is 60 from a quarter of an inch to three eighths. A suitable thickness of plate is about 4 to 8 oz. to the square foot, while the number of corrugations or folds is conveniently about twelve to the inch. The edges *c*, Fig. 3 are 65 flattened and held between two slats *d* and *e*, which are conveniently of semicircular section. The slats are interconnected or fixed by wood or like pins *f*, at suitable intervals. A similar fixture is provided at each side as 70 can be seen in Fig. 1. Transverse rigidity is obtained by top and bottom transverse distance pieces *g* and *h*. The bottom transverse distance piece *g* is conveniently provided with a V-shaped channel *k* in which the 75 V-shaped ends of the corrugations nest. The slats *d*, *e* are conveniently fixed in the bottom distance piece *g* by means of pins of wood or the like *j*. The upper distance piece *h* is also channeled to engage over the upper 80 corrugations, while the interconnected side slats *d*, *e* pass through guide holes *m* in the top distance piece. This arrangement enables the plate to expand or "grow" 85 longitudinally, as occurs in practice during the process of forming, without any danger of the plate becoming distorted. The terminal is produced by forming an extended portion at the upper edge of the plate and bunching together the corrugations of this 90 extended portion so as to form a tongue *n*. From this tongue lead or like bars *o*, *p* extend on each side laterally and continue vertically down the sides of the plate at *q*, *q*, whereby an even distribution of the current 95 density is obtained. The tongue portion *n*, extends through a slot in the top distance piece *h*. A number of perforations *x* are also provided on this top distance piece to permit of escape of gas from the cell. The 100 distance pieces *h* and *g* are preferably of the same width as the corrugations so as to prevent the formation of a ledge on which dirt could collect and eventually cause short circuiting.

During the process of forming the plates, additional rigidity is supplied by using temporary transverse intermediate slats *u*, *v* which may be held in place by rubber bands *w* sprung over their edges where they pro- 105 110

ject at the sides as seen in Fig. 1. After the plate has been formed completely these temporary slats are removed.

With an accumulator plate as illustrated, the reinforcing means do not cover or render inactive any material proportion of the plate and the rigidity secured is sufficient to enable the plate to be made in one piece without panels, while the construction of the reinforcing means is such as to give free play for the plate to "grow" during the process of formation. The reinforcing means further is of an extremely light nature whereby the plate is considerably lightened and rendered more suitable for use in vehicles. By arranging the corrugations vertically greater freedom of access to all parts of the surface by the electrolyte is given and when the plate is used in a vehicle the jolting and vibration of the vehicle causes the electrolyte to wash well over the entire available surface. By bunching the vertical corrugations together to form a tongue, the corrosion which occurs in those plates in which a terminal portion is burnt on to the plate is entirely avoided while a better electrical connection is secured.

When the plate is being formed it may be moved and manipulated by seizing it by means of the projecting ends m' . When the plate is completely formed the top piece h is pressed down in place whereby the plate after formation and when in a brittle state may be handled by gripping the top bar h .

In a second form of the invention a plate a' is first cast in lead of comparatively thick material and with shallow corrugations and with thicker ribs 9 and 10. The ribs 9 are formed at the edges, and the ribs 10 across the plate at various positions running transversely and vertically. The plate is then pressed between suitable dies so that the corrugations of the plate are made thin and the ribs 9 and 10 are pressed to the form shown in Fig. 5. Wooden slats c and a transverse bottom stiffening piece g having grooves to receive the ribs closely engage with the ribs as indicated in Figs. 6 and 7. An upper stiffening piece h , is adapted to slide on the side slats c and to engage with the top rib 9 of the plate this piece h being of similar form to that hereinbefore described with reference to Figs. 1 and 2, corresponding parts being similarly lettered.

The terminal n in the form of plate shown in Fig. 8 is integral with the upper rib 9. By the above construction a plate can be produced of adequate rigidity and lightness without necessitating any metal jointing or burnt parts.

It is to be understood that the plates are preferably used in the vertical position as indicated in Figs. 1 and 8, but I may, should such be found more convenient, arrange the plates with the longer edges horizontal.

I claim.

1. An accumulator plate comprising a single sheet of corrugated lead having grooved wooden slats fitting the side edges of said plate and top and bottom grooved distance pieces fitting the top and bottom edges of said plate, said top distance piece being adjustable relatively to said side slats substantially as and for the purpose hereinbefore set forth.

2. An accumulator plate of corrugated lead having solid ribs along its side and top and bottom edges, and other solid ribs crossing said plate both transversely and vertically, grooved wooden slats adapted to fit the ribs at the side edges of the plate, 80 grooved distance pieces adapted to fit the ribs at the top and bottom edges, said top distance pieces being adjustable relatively to the said slats, substantially as and for the purpose hereinbefore set forth.

3. An accumulator plate of corrugated lead having solid ribs along its side and top and bottom edges, and other solid ribs crossing said plate both transversely and vertically, grooved wooden slats adapted to fit the 90 ribs at the side edges of the plates and top and bottom grooved distance pieces adapted to fit the ribs at the top and bottom edges, said top distance pieces being adjustable relatively to the said slats, said adjustable 95 top distance piece having an aperture, and a terminal integral with the adjacent rib and adapted to pass through said aperture substantially as hereinbefore set forth.

In testimony whereof I have signed my 100 name to this specification in the presence of two subscribing witnesses.

GRIFFITH OWEN DAVIES.
